(57) **CLAIM**

The ornamental design for a bed frame as shown and described.

DESCRIPTION

FIG. 1 is a top, front and right side perspective view of a bed frame with a bed board disassembled from the bed frame showing our new design;

FIG. 2 is an enlarged view of portion 2 in FIG. 1;

FIG. 3 is a top, front and left side perspective view thereof with the bed board disassembled from the bed frame;

FIG. 4 is a top, rear and left side perspective view thereof with the bed board disassembled from the bed frame;

FIG. 5 is an enlarged view of portion 5 in FIG. 4;

FIG. 6 is a top, rear and right side perspective view thereof with the bed board disassembled from the bed frame;

FIG. 7 is a top, front and left side perspective view showing the bed frame in a raised position, wherein the bed board is disassembled from the bed frame and is bended;

FIG. 8 is an enlarged view of portion 8 in FIG. 7;

FIG. 9 is a top, front and right side perspective view showing the bed frame in the raised position, wherein the bed board is removed;

FIG. 10 is an enlarged view of portion 10 in FIG. 9;

FIG. 11 is a top, rear and left side perspective view showing the bed frame in the raised position, wherein the bed board is removed and one side of supporting mechanism is removed;

FIG. 12 is a top plan view thereof, wherein the bed board is removed;

FIG. 13 is a left side view thereof;

FIG. 14 is a left side view thereof in the raised position;

FIG. 15 is a right side view thereof in the raised position;

FIG. 16 is a rear elevational view thereof, wherein the bed board is removed; and,

(Continued)

FIG. 17 is a front elevational view thereof, wherein the bed board is removed.

The broken lines in the drawings illustrate portions of the bed frame which form no part of the claimed design.
